CLAIM

The ornamental design for a bike trailer tent, as shown and described.

DESCRIPTION

FIG. 1 is a front, top perspective view of a bike trailer tent, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1; and,

FIG. 10 is another perspective view of the bike trailer tent, shown in a position of use.

The dash dot dash lines in FIGS. 1 and 9 are for the purpose of illustrating the enlarged view indicators and form no part of the claimed design. The evenly spaced dash lines are shown for the purpose of illustrating both parts of the bike trailer tent as well as environmental subject matter. None of the broken lines form part of the claimed design.
